UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed January 7, 1924. Serial No. 684,750.

My invention relates to drilling mechanism.

An object of my invention is to provide an improved drilling mechanism. Another 5 object of my invention is to provide an improved drilling mechanism having an improved pressure fluid operated feeding mechanism having improved controlling means therefor. A further object of my invention 10 is to provide an improved feeding mechanism for pressure fluid rock drills having improved means for controlling the operation thereof. A still further object of my invention is to provide an improved feeding mechanism for pressure fluid rock drills 15 of the percussive type having improved automatic feed controlling mechanism whereby the rate of feed is automatically controlled in accordance with the nature of the 20 drilling. Still another object of my invention is to provide improved means for "spotting" the drill hole and for preventing excessive rates of feed when a cavity or soft spot is encountered. These and other objects and advantages of my invention will, 25 however, hereinafter more fully appear.

In the accompanying drawings I have, for purposes of illustration, shown one form which my invention may assume in practice.

30 In these drawings,—

Fig. 1 is a side elevation of a rock drilling mechanism in which an illustrative form of my invention is embodied, the view being partially broken away in central longitudinal section to facilitate illustration.

Fig. 2 is a central longitudinal vertical sectional view of my improved controlling mechanism taken substantially on line 2—2 of Fig. 1, the view being partially in elevation.

Fig. 3 is a transverse sectional view through the rotation and percussive motors taken substantially on line 3—3 of Fig. 1.

Fig. 4 is a transverse sectional view taken 45 substantially on line 4—4 of Fig. 2.

In this illustrative form of my invention I have shown a rock drilling mechanism of the so-called "stopper" type, generally designated 1, especially adapted to use in stopes comprising a drilling motor 2 and a feeding mechanism 3. Herein, the drilling motor is of the pressure fluid percussive type comprising a cylinder 4 having a bore 5 in which a hammer piston 6 is reciprocably mounted 50 and adapted to percussively actuate a drill

steel 7 suitably carried in a chuck 8 arranged within the front end of the drilling motor 2. The feeding mechanism 3 is of the pressure fluid operated type and comprises a cylinder 9 arranged in alinement with the drilling motor and having a bore 10 in which a washer packed piston 11 is disposed provided with a piston rod 12 suitably secured thereto. This piston rod is provided with longitudinally extending splineways 13 which cooperate with splines 14 suitably carried in the rear head 15 of the feed cylinder and which piston rod terminates in a foot piece 16 pivoted at 17 thereon provided with points 18 adapted to engage a suitable extraneous abutment or support during the drilling operation, herein the mine bottom.

Herein, it will be observed that interposed between the drilling motor 2 and the feeding mechanism 3 is a head block 19 which closes the rear end of the cylinder bore 5 and the front end of the feed cylinder bore 10 and which incorporates a portion of my improved controlling mechanism to be hereinafter described. The feeding mechanism, the head block, and the drilling motor parts are rigidly held in the desired assembled relation by side rod connections 20, in a well known manner. Suitably secured to 75 the head block 19 is a laterally projecting handle 21 which is employed in supporting the drill at certain times during the drilling operation.

An independent pressure fluid actuated rotation motor, generally indicated 22, is provided to rotate the drill steel 7 and which comprises a pair of intermeshing toothed rotors 23 and 24 disposed in a bore 25 formed in the drilling motor cylinder 4. The rotor 23 is operatively connected through a shaft 26, disposed parallel with the cylinder bore 5, mounted in suitable bearings and provided with a pinion 27 meshing with a gear 28 formed on the chuck 8. Herein the motor 22 is provided with an exhaust chamber 29 which communicates by way of a passage 30 with an enlarged chamber 31 surrounding the shaft 26, and which communicates with the atmosphere by means of a series of small 90 ports 32 which muffle or silence the screech produced when air passes through motors of this type. Pressure fluid is supplied to the machine through a pipe connection 33 controlled by a throttle valve 34 having an oper- 100 105 110

ating lever 34' and disposed in a boss formed on the head block 19, from any suitable source of supply, and passes through a port 35 to the feed cylinder 9 and a passage 36 5 to the inlet chamber 37 of the rotation motor, and through a passage (not shown) to the distribution ports of the motor 2, in the usual manner.

In my improved construction it will be 10 noted that the feed piston rod 12 is provided with a longitudinally extending bore 38 which is filled with liquid, herein oil, and in which a piston 39 is slidably mounted and secured to a longitudinally extending rod 15 40 suitably secured to the head block 19 by means of a collar member 41 which engages an annular flange 42 formed on the upper end of the rod. Herein it will further be noted that this rod 40 passes through suitable packing or cup washers 43 carried by 20 the piston 11 which prevent leakage of fluid between the cylinder bore 38 and the air cylinder 10, while the piston 39 is provided with packing or cup washers 44 which prevent 25 leakage of fluid from one side of the piston to the other. Bypass ports 45 and 46 are formed in the rod 40 which permit oil to pass to the opposite sides of the piston 39 under the control of an automatic 30 control valve generally designated 47. This automatic control valve comprises a body portion 48 grooved at 49 and having a head 50 movable in a pressure tight chamber 51, which is closed by a plug 52 through which 35 a plunger 53 is slidable having a push button 54 formed on its outer end which is adapted to be manipulated by the operator at certain times during the drilling operation. A spring 55 holds the plunger in its inoperative 40 position. The body portion of the valve is slidable in a bore 56 which is closed by a suitable plug member 57 adapted to adjust the pressure on a spring 58 acting on the valve, tending to hold it in its wide open 45 position. By changing the tension of this spring, the rate of feed may be varied. On the left hand side of the head 50 the chamber 51 is vented to the atmosphere by way of a small port 59. A passage 60 leads from the 50 inlet chamber 37 of the rotation motor 22 to the right hand end of the head 50 (see Fig. 2). The type of automatic control valve shown is used for illustrative purposes only, the particular type of valve used being immaterial.

In the operation of my improved mechanism, it will be noted that the points 18 of the foot piece 16 are placed against a stationary abutment a suitable distance from 60 the working face, the operator holding the drill in position at this time by means of the handle 21. The throttle valve 34 is then manipulated admitting pressure fluid to the feeding mechanism, bringing the bit of the 65 drill steel 7 adjacent the work. Pressure

fluid is then admitted to the drilling motor 2 and rotation motor 22 thereby causing the drill steel to be percussively actuated and rotated. It will herein be noted that at this time the valve 47 is in its wide open position, 70 as shown in Fig. 2, with the oil bypassing from the bore 38 above the piston 39 through the passage 45, the groove in the valve, and the passage 46 communicating with the bore 38 below the piston 39. The operator then 75 presses on the push button 54, cutting off communication between the bypass ports 45, 46, preventing relative movement between the piston 11 and the cylinder 9 and permitting the "spotting" of the hole. After 80 the hole is "spotted" the push button is released and the spring 58 forces the automatic control valve 47 again to its wide open position, the pressure in the inlet side of the rotation motor being relatively low at this 85 time, due to the restricted size of the inlet port 36 and the comparatively rapid fluid consumption of the motor 22, and permitting the oil to flow from the upper part of the chamber 38 to the lower part of this chamber 90 below the piston 39. If soft or sticky drilling is encountered, the rotation of the drill steel is resisted, thereby causing the rotation motor to slow down to a certain extent and building up the pressure in the inlet chamber 95 37 which passes through the port 60 to the right hand side of the head 50 of the valve 47, causing it to move slightly to the left from the position shown in Fig. 2 and cutting down the amount of oil flow through the bypass passage 46, consequently slowing down the feed. As the resistance to rotation increases, the amount of oil flow through the port 46 is diminished. If a cavity or opening 100 is encountered, the oil cylinder 38 has a dashpot action on the feed which prevents an excessive rate of feed and thereby prevents the consequent sticking or jamming of the drill steel in the hole. It is obvious that the operator may control the rate of feed at 105 will by the suitable manipulation of the push button 54 varying the oil flow through the bypass ports 45 and 46.

As a result of my invention, it will be 110 noted that I have provided an improved pneumatically fed drilling mechanism having improved automatic controlling mechanism which controls the rate of feed in accordance with the nature of the drilling encountered and prevents excessive rates of 115 feed when a soft spot or cavity is encountered while the strength of the feed may also be manually controlled at will by the operator. These and other advantages will be clearly apparent to those skilled in the art. 120

While I have in this application specifically described one form which my invention may assume in practice, it will be understood that this form of the same is shown 125 for purposes of illustration and that the in- 130

vention may be modified and embodied in various other forms without departing from its spirit or the scope of the appended claims.

What I claim as new and desire to secure

5 by Letters Patent is:

1. In drilling apparatus, a drilling tool, a plurality of motors for actuating said tool one of which is rotary, and hydraulic resistance means controlled by one of said 10 motors for automatically controlling another to vary the operation of said tool and including a fluid resistance body displaceable upon movement of said latter motor.

2. In drilling apparatus, a drilling tool, 15 a rotary motor for rotating said tool, feeding means for said tool, and hydraulic resistance means responsive to pressure conditions within said rotary motor for controlling said feeding means and including a 20 displaceable fluid body resisting feeding movement of said feeding means.

3. In drilling apparatus, a drilling tool a rotary motor adapted to rotate said tool, feeding means for said tool, and hydraulic 25 resistance means responsive to the resistance to rotation of said tool for automatically controlling said feeding means and including a fluid resistance body displaceable upon movement of said feeding means.

30 4. In drilling apparatus, a drilling tool, a plurality of tool actuating motors one of which is rotary, feeding means for said tool, and hydraulic resistance means controlled by one of said motors for automatically 35 controlling said feeding means and including a displaceable fluid body resisting feeding movement of said feeding means.

5. In drilling apparatus, a drilling tool a pressure fluid actuated rotary motor for 40 rotating said tool, feeding means for said tool, and hydraulic resistance means responsive to the variations of pressure within said motor for controlling said feeding means and including a displaceable fluid body resisting feeding movement of said feeding means.

45 6. In drilling apparatus, a drilling tool, a plurality of fluid actuated motors for actuating said tool, one of which is rotary, and hydraulic resistance means responsive to the variations of pressure within said 50 rotary motor for automatically controlling another to vary the operation of said tool and including a fluid resistance body displaceable upon movement of said latter motor.

55 7. In a drilling mechanism, a drilling motor adapted to percussively actuate a drill steel, means for rotating the drill steel, means for feeding the steel forward, and pressure fluid means responsive to the resistance to rotation for automatically resisting said forward feeding means operative to provide, in accordance with variations in 60 resistance, variations in the rate of forward

feed without interrupting the same and including a fluid resistance body displaceable upon feeding movement of said feeding means.

8. In a drilling mechanism, a drilling motor adapted to percussively actuate a drill steel, means for rotating the drill steel, pressure actuated means for feeding the steel forward, and pressure fluid means responsive to the resistance to rotation for automatically resisting said forward feeding means operative to provide, in accordance with variations in resistance, variations in the rate of forward feed without interrupting the same and including a fluid resistance body displaceable upon feeding movement of said feeding means.

70 9. In a drilling mechanism, a drilling motor, a rotation motor, feeding means for said drilling motor, pressure fluid means for controlling said feeding means and including a fluid resistance body displaceable upon feeding movement of said feeding means, and automatic means responsive to the resistance to rotation for operating said pressure fluid controlling means.

75 10. In a drilling mechanism, a drilling motor adapted to operate on a drill steel, pressure fluid feeding means therefor, independent means for rotating the drill steel, and means responsive to the resistance to rotation for automatically controlling said feeding means while the feeding pressure in the feeding means remains substantially constant and including a fluid resistance 80 body resisting feeding movement of said feeding means and displaceable upon feeding movement of said feeding means.

85 11. In a drilling mechanism of the hammer type, the combination of means for rotating the drill steel, means for feeding the steel forward, and means controlled by the resistance to rotation for automatically controlling said forward feeding means and for preventing an excessive rate of forward 90 feed when the resistance to rotation is removed, said automatic means being operative to provide, in accordance with variations in resistance, variations in the rate of forward feed without interrupting the same.

105 12. In combination, work performing means comprising a rotary motor, feeding means therefor, and controlling means for said feeding means comprising a fluid displaced upon movement of said feeding means and automatic means controlled by said motor for interrupting displacement entirely or providing different continuous rates of displacement.

110 13. In combination, work performing means comprising a rotary motor, feeding means therefor, controlling means for said feeding means comprising a fluid displaced upon movement of said feeding means, and automatic means controlled by said motor 115

for providing varied continuous rates of displacement in one direction.

14. In a drilling mechanism, a drilling motor adapted to percussively actuate a drill steel, rotating means for said drill steel, feeding means for said steel, controlling means for said feeding means comprising a substantially incompressible fluid displaced upon movement of said feeding means, and automatic means responsive to the resistance to rotation for automatically controlling the amount of fluid displaced.

15. In a drilling mechanism, a drilling motor, feeding means therefor, pressure fluid resistance means disposed within said feeding means for controlling movement thereof and including a fluid resistance body displaceable upon feeding movement of said feeding means, and means including a push button for manually controlling said last mentioned means.

16. In a drilling mechanism, a drilling motor of the hammer type, a motor actuated by pressure fluid for rotating a drill steel, pressure fluid feeding means including a co-operating cylinder and piston, pressure fluid means for resisting said feeding means in-

cluding a displaceable fluid resistance body opposing feeding movement and an automatic controlling mechanism for said fluid resistance body responsive to variations of pressure within said rotation motor.

17. In a rock drilling mechanism, a drilling motor adapted to actuate a drill steel, means for rotating the drill steel, means for feeding the drill steel, and hydraulic controlling means including means responsive to the resistance to drill steel rotation for automatically controlling said feeding means and comprising a displaceable fluid resistance body opposing feeding movement of said feeding means.

18. In combination, a drilling motor adapted to actuate a drill steel, rotation means for the drill steel, feeding means for the steel, and means for controlling said feeding means comprising a liquid variably displaced upon variations of resistance to rotation of the drill steel and means responsive to the resistance to steel rotation for providing varied continuous rates of liquid displacement.

In testimony whereof I affix my signature.
CHARLES F. OSGOOD.
